(57) **CLAIM**

The ornamental design for an adjustable pedestal, as shown and described.

DESCRIPTION

FIG. 1 is a bottom view of an adjustable pedestal showing our new design;

FIG. 2 is an isometric view thereof;

FIG. 3 is an inverted isometric view thereof;

FIG. 4 is a left side view, the rear and the front view being identical to the left view thereof; and,

FIG. 5 is a top view thereof.

The broken line showing in the figures is included for the purpose of illustrating environment and forms no part of the claimed design.
